CLAIM

What is claimed is the ornamental design for a wireless charger, as shown and described.

DESCRIPTION

FIG. 1 is a top, rear and left side perspective view of a wireless charger showing our new design;

FIG. 2 is a top, front and right side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof; and,

FIG. 9 is a bottom, rear and right perspective view of the wireless charger of FIG. 1, enlarged for clarity of disclosure and shown in a condition of use.

The broken lines depict portions of the wireless charger that form no part of the claimed design. The wireless charger is shown with symbolic breaks in its length in FIGS. 1-8. The appearance of any portion of the article between the break lines forms no part of the claimed design.
